By G. Pilechowicz
ATTY.

UNITED STATES PATENT OFFICE

WOJCIECH W. WUJCIK, OF CHICAGO, ILLINOIS

FURNITURE PIECE

Application filed February 7, 1930. Serial No. 426,491.

The present invention relates to easy chairs, its principal object being the provision of chairs combined in one unit.

A further object of the invention is the provision of two chairs combined and laterally joined together and each facing in opposite direction with relation to the other.

A further object of the present invention is the construction of a furniture piece of the character stated which may have suitably formed frames of practical and durable construction.

With the above general objects in view and others that will appear as the nature of the invention is better understood, the same consists in the novel combination, construction and arrangement of parts hereinafter more fully described, illustrated in the accompanying drawing and pointed out in the appended claim.

In the drawing forming a part of this application, and in which like designating characters refer to corresponding parts throughout the several views,

Fig. 1 is an elevational perspective view of the present invention, while the same is in an upholstered condition; and

Fig. 2 is an enlarged elevational perspective view of the frame forming the basis for the present invention.

Referring to the present drawing there is shown therein a substantially rectangular base frame including a pair of longer sides 10 and a pair of end sides 11, said side members 10 being substantially twice as long as the end members 11.

Upwardly projecting from a pair of diagonally disposed corners of said base frame are uprights 12. Similar uprights 13 upwardly project, one from the center of each side member 10 of the base frame, said uprights 13 being oppositely disposed with relation to each other and in transverse relation to the frame. Uprights 12 and 13 on each side of the base frame are connected at their upper ends by arch pieces 14, said uprights 12 and 13, and arch pieces 14, on each side of said base frame constitute backs 14' as shown on Fig. 1, for each of the two chairs in their unitary formation.

From the other two diagonally disposed corners of the base frame supports 15 upwardly project, said supports 15 being oppositely disposed with respect to the adjacent upright member 12 at each end of the device. Braces 16 are rigidly affixed to the upper ends of supports 15 and are connected by their other ends to the adjacent uprights 12, said braces 16 constituting arm rests 16' in the finished and upholstered furniture piece, as seen on Fig. 1. Said braces 16 are substantially in alignment with the end members 11 of the base frame.

On horizontal plane with braces 16 is a similar brace 17 connecting the opposite upright members 13 adjacent their upper ends, said brace 17 constituting a common arm rest 17' at the common adjacent side of the two oppositely disposed chairs while the same are in a unitary formation, as seen on Fig. 1.

To strengthen the structure of the device, as well as to provide additional skeleton for upholstering, uprights 12 and supports 15 at each end of the device as well as uprights 13, at the lower ends are connected by lower braces 18 and 19, respectively. On the same plane with said braces 18 and 19 are braces 20 connecting uprights 12 with uprights 13 at each side of the base frame.

Said base frame at each corner thereof is provided with downwardly projecting legs 21.

The frame for the device as shown on Fig. 2 is to be suitably padded and upholstered and provided with seat cushions 22 for each chair, as shown on Fig. 1.

From the hereinabove description it will be apparent that the device herein disclosed consists of two chairs oppositely disposed in respect to each other so that two persons using the same will face each other.

While there is described herein a preferred embodiment of the present invention it is nevertheless to be understood that minor changes may be made therein without departing from the spirit and scope of the invention as claimed.

What I claim as new is:

A furniture piece of the class described comprising a rectangular frame including a

pair of longer side members and a pair of shorter end members, upright members extending from the two diagonally disposed corners of said frame, upright members extending from the central portions of said longer side members of said frame, arch members connecting the two adjacent upright members at each longer side of said frame, said each respective pair of upright and said 10 arch members on each side of the frame constituting a skeleton to be covered with upholstery thus providing a pair of backs for the furniture piece, supports upwardly extending from the other diagonally disposed corners of said frame, braces connecting said supports with the upright members at the opposite side of said frame, said braces furnishing a skeleton for upholstery and constituting arm rests for the furniture piece, a brace connecting the opposite upright members extending from the central portions of the longer sides of said frame, said latter brace also furnishing a skeleton for upholstery and constituting a common arm rest co- 20 operating with said two backs, and a plurality of auxiliary braces connecting said upright members with each other and said supports with said upright members, said auxiliary braces serving both to strengthen the 25 structure and to provide additional skeleton 30 for upholstery.

In testimony whereof I affix my signature.
WOJCIECH W. WUJCIK.
